ROCKING TOY

Paul W. Miessler, Sr., Berea, Ohio, assignor to The Patent and Licensing Corporation, New York, N.Y., a corporation of Massachusetts

Filed Dec. 8, 1959, Ser. No. 858,096
6 Claims. (Cl. 46—115)

This invention relates to a toy of the rocking type, and more particularly to a toy of this type having educational value as well.

An object of the invention is to provide a toy of this character which will permit a child to impart rocking motion thereto for amusement, and at the same time enable the child to gain the fun and educational value of playing with animal figures.

Another object of the invention is to provide a toy of the character aforesaid which can be produced entirely from fibreboard such as corrugated paperboard, and hence at a very low cost.

Still another object is to provide a fibreboard toy of the character described which can be stored and packed for shipment in flat form, and easily set-up and assembled by a child, to form the operative toy.

Briefly stated, the toy according to the invention comprises (1) a base member formed of a single flat piece of fibreboard, scored for folding along parallel lines to provide a top wall and a pair of side walls depending therefrom and having convexly curved bottom edges on which the toy may be given rocking motion, and (2) an upper member formed for detachable engagement with the base member, arranged to extend vertically upward from the top wall of the base and configured and demarcated, as by suitably imprinting the same, to simulate the body of an animal in profile.

The construction and arrangement of the parts may be such as to enable differently configured and demarcated upper members, simulating different animals in profile, to be interchangeably used with one base member. However, in actual practice, it may be desirable or preferable to package the toy as a set composed of a number of the base members and a corresponding or even greater number of upper members, differing from one another in configuration or design, thereby enabling the child to erect more than one of the complete devices for playing with or displaying them simultaneously.

The invention will be more readily understood from the detailed description below and from the accompanying drawings, in which:

FIG. 1 is a perspective view of a toy embodying the invention;

FIG. 2 is a view in vertical cross-section, taken along line 2—2 of FIG. 1;

FIG. 3 is a fragmentary view, partly in elevation taken along line 3—3 of FIG. 2;

FIG. 4 is a plan view of the blank or collapsed piece of fibreboard constituting the base member of the toy;

FIG. 5 is a view, in elevation, of a detachable upper member for use with the base member of FIG. 4, appropriately configured to simulate, for example, the body of a sitting rabbit.

As shown in the drawing, the toy according to the invention comprises a base member, indicated generally by letter B, and constituting the rocker element of the complete toy; and a detachable upper member, indicated generally by letter A, and constituting the animal-simulating element thereof.

Referring particularly to FIG. 4, the base member B is in the form of a single piece of corrugated fibreboard, or the like, of sufficient stiffness to sustain the erected

2

shape of the base when folded as hereinafter described.

As shown, the base member, in its collapsed or flattened form, comprises a relatively elongated, pre-cut blank 10, having its opposite longitudinal edges 11, 12 convexly curved symmetrically with respect to the longitudinal center line of the blank, and having parallel end edges 13, 14. Although the curved portions of the edges 11, 12 are shown as terminating respectively at aligned longitudinal edges 15, 16, it will be understood that the curvature of the edges 11, 12 may be such that they terminate at the end edges 13, 14.

The member 10 is formed on its bottom face with a pair of aligned longitudinal scores 19 extending inwardly from the end edges 13, 14 at any desired distance from the ends of the convexly-shaped edge 11, and with a parallel pair of aligned longitudinally scores 20 also extending inwardly from the end edges at a corresponding distance from the ends of the opposite convexly-shaped edge 12. Member 10 is also formed on its bottom face, with scores 21, 22, intermediate and parallel to the scores 19, 20, and spaced transversely outward with respect to score lines 19 and 20, respectively.

Connecting the corresponding ends of the scores 21, 22 are transversely extending, parallel slits 23, intersecting the inner ends of the respective pairs of parallel scores 19 and 20.

Along its longitudinal center, the member 10 is formed with a slit 25, preferably parallel to the scores 19, 20, 21 and 22. Each opposite end of slit 25 bisects one of the transverse slits 23.

As will be seen, member 10 thus has within its confines a pair of spaced end panels 27, 28 (bounded by an end edge 13 or 14, scores 19, 20, and portions of transverse slits 23) and a pair of separable panel sections 29, 30, panel section 29 being bounded by score 21, portions of transverse slits 23 and longitudinal slit 25, and panel section 30 being bounded by score 22, portions of slits 23 and longitudinal slit 25.

The panel sections 29, 30 are each provided with longitudinally extending relatively elongated slots 31, 32 respectively, each spaced the same distance transversely from the longitudinal slit 25.

Desirably also, the blank is formed with relatively short longitudinal slots 35, 36, preferably in longitudinal alignment with one another and with the slit 25, and extending outwardly of the slits 23 into the respective panel sections 27, 28.

The width of the slots 31, 35 and 36 corresponds substantially to the thickness of the material of which the lower or attaching end of member A is formed.

As will be seen, particularly from FIGS. 1 and 2, the base member B of the toy may be readily set-up by folding the same along the hinge lines provided by scores 19, 20, to bring the portions 37, 38 into depending position relative to the panel sections 27, 28, and folding the panel sections 29, 30 along the hinge lines provided by the scores 21, 22. The panels 27, 28 will thus constitute the top of the base, the downfolded depending sections 37, 38 will thus constitute the side walls thereof, their convexly curved edges 11, 12 serving as the runners for imparting rocking motion to the base, and the panel sections 29, 30 will overlap and constitute a downwardly recessed portion of the top wall of the base.

The panel sections 29, 30 are infolded so as to overlap one another in a position such that one of the slots 31, 32 registers or coincides with the other, to receive the lower portion of the detachable upper member A, thereby also retaining the panels 29, 30 in overlapped position and preventing collapse of the base from its set-up position by the normal tendency of the portions 37, 38 otherwise to move back along scores 19, 20 into the plane of the sections 27, 28.

The upper member A is preferably also made of a flat piece of corrugated fibreboard. However, if desired, this member, which serves as the animal-simulating portion of the toy, may have the portion thereof, which is exposed to view in the assembly, of three-dimensional character rather than of flat sheet material. This may be done, for example, by suitably embossing the flat sheet of fibreboard from which it is produced, or by utilizing as the material for the member A, suitably molded pulp board, or suitably molded plastic material, particularly any of the relatively inexpensive synthetic resin plastics commercially available.

The upper member A has its portion 40 configured to correspond substantially to that of an animal, and demarked or decorated on its surface, as by suitable imprinting, to simulate the appearance of the body of an animal in profile.

The member A has its lower portion 41 formed for detachable engagement of member A with the base member B in the assembled toy. To that end, in the embodiment illustrated, the lower portion 41 may be in the form of a relatively elongated portion terminating in vertical edges 42, 42, and having aligned horizontal edges 44, 45 spaced by an intermediate bottom extension 47. To retain member A in locked position on base member B, the extension 47 is formed adjacent one of its ends with a hinged locking tab, as illustrated by tab 50, hinged along vertical score 48 and separated from portion 41 by a short horizontal slit 49 located at a distance below edge 44 corresponding substantially to twice the thickness of which the portion 41 is formed.

As will be seen, the toy may be readily assembled for use by inserting portion 41 into coinciding slots 31, 32 of the base member, and moving tab 50 into an angular position to lock the parts together. As shown in the drawing, opposite ends of the portion 41 are received by the slots 35, 36 in the top wall sections 27, 28, reinforcing the assembly and retaining the animal-simulating upper member A in firm, yet detachable, position on the base member B.

As will be apparent, the toy construction according to the invention will not only afford amusement to a child, by reason of the rocking motion which the child may impart to the toy, but will also serve an educational function in respect of the animal-simulating effect obtained therewith. By providing a plurality of upper members A, differently configured and decorated to simulate a variety of animals, for interchangeable use with the base, the interest of the child will be enhanced and maintained. Also, as already stated, it may be desirable, in commercial practice, to supply the toy in a package containing a plurality of base members B, together with a corresponding number of upper members A configured and decorated differently from one another to simulate a variety of animals, thus enabling the child to set up and assemble as many of those in the set as desired, for simultaneous play and study.

I claim:

1. A toy of the character described, consisting essentially of a relatively elongated base member and a detachable upper member, said base member comprising a sheet of fibreboard scored longitudinally of the base to provide a top wall and a pair of side walls hinged thereto in depending position, said side walls having convexly curved bottom edges enabling said base to be given rocking motion on a supporting surface, said base member being cut and scored centrally thereof to provide spaced panels constituting said top wall, and a recessed portion intermediate said panels, said panels being disposed in a common plane and said recessed 70

portion comprising transversely over-lapped panels disposed in a plane below said common plane when said side walls are disposed in depending position with respect to said top wall, said base member and the lower end of said upper member being formed with means to detachably connect said upper member with said base member and to retain said panels in said overlapped position, said upper member being configured to simulate an animal in profile.

10 2. A toy as defined in claim 1, wherein said means comprises an opening formed in each of said panels, an opening in one of said panels registering with that in the other of said panels in the overlapped position of the panels.

15 3. A toy of the character described, consisting essentially of a fibreboard base in the form of a rockable member, and a detachable element configured and demarked to simulate an animal, said base comprising an intermediate portion, side portions foldable into depending position with respect to said intermediate portion, the marginal edges of said side portions being of symmetrical convex curvature with respect to the longitudinal center line of said base, said convex edges extending in parallel planes throughout their length when said side portions

20 25 are in depending position, said intermediate portion comprising a pair of spaced end panels lying in a common plane and constituting the top surface of said base and a pair of panels intermediate said end panels, said intermediate panels being transversely overlappable in a plane spaced below said common plane when said side portions are folded into depending position as aforesaid, and said intermediate portion being formed with means to engage the lower portion of said detachable element whereby to retain said element in position on said base and in engagement with said overlapped panels.

30 35 4. A toy as defined in claim 3, wherein said means comprises openings formed in said intermediate panels, said openings being in register with one another in the overlapped position of said intermediate panels.

40 5. A toy as defined in claim 4, wherein said detachable element is formed with an extension at one end thereof for insertion in said registered openings, said extension being formed with a hinged tab to retain said detachable element in firm engagement with said openings.

45 55 6. A one-piece blank of fibreboard adapted to form a rocker element for a toy of the character described, said blank having a pair of opposed arc-shaped side edges, a pair of end edges, pairs of aligned, longitudinal score lines extending from each of said end edges, a longitudinal score line parallel to and spaced laterally outward with respect to each of said first-named aligned pairs, a transversely extending slit connecting the corresponding ends of said second-named score lines, a longitudinal slit extending centrally of said blank and intersecting said transverse slits to form separate panel portions which overlap one another when said blank is folded along said first-named aligned pairs of score lines and said panel portions are folded along said second-named score lines, each of said panel portions having an opening formed therein, said openings being positioned so as to be brought into registry with one another when said panel portions are overlapped as aforesaid, for engaging a separate member of said toy with the thus folded blank.
